COAXIAL SWITCH

Jo Emmett Jennings, San Jose, Calif., assignor, by mesne assignments, to Jennings Radio Manufacturing Corporation, San Jose, Calif., a corporation of Delaware
Filed May 18, 1959, Ser. No. 813,935
11 Claims. (Cl. 200—144)

The invention relates to coaxial switches, and particularly to a vacuumized miniature coaxial switch.

One of the objects of the invention is the provision of a single pole-double throw vacuum coaxial switch having a low voltage standing-wave-ratio.

Another object of the invention is the provision of a vacuum coaxial switch shielded against power leakage and the effects of radiation from other sources.

Still another object of the invention is the provision of a vacuum coaxial switch operable remotely by an external solenoid utilizing any practical A.C. or D.C. voltage.

Still another object of the invention is the provision of a vacuum coaxial switch of substantially 5 kw. capacity and of extremely small size in comparison with conventional coaxial switches having comparable power ratings.

A still further object of the invention is the provision of a vacuum coaxial switch requiring minimum power to operate, and constructed from materials and in a manner requiring little machining and custom processing so as to maintain manufacturing costs at a minimum.

The invention possesses other objects some of which with the foregoing will be brought out in the following description of the invention. I do not limit myself to the showing made by the said description and the drawings, since I may adopt variant forms of the invention within the scope of the appended claims.

Referring to the drawings:

FIG. 1 is a vertical half-sectional view, partly in elevation, showing the switch contact in its normal spring-closed position. The solenoid-closed position of the switch contact is shown in dash lines.

FIG. 2 is a horizontal sectional view taken in the plane indicated by the line 2—2 of FIG. 1.

FIG. 3 is a vertical sectional view taken in the plane indicated by the line 3—3 of FIG. 1.

FIG. 4 is a fragmentary sectional view illustrating a modified contact structure.

All of the figures are drawn approximately four times actual size.

Broadly considered, the miniature vacuum coaxial switch of my invention comprises a vacuumized envelope including an outer metallic conductor or hermetically sealed shell. Arranged within the outer conductive shell and rigidly supported thereon are a plurality of inner conductors which extend hermetically through the envelope wall and provide spaced contact points within the envelope and terminal leads outside the envelope. The outer metallic shell is preferably cruciform in shape so as to accommodate two axially aligned and spaced transversely extending contact points perpendicular to and spaced from a third common contact point, all of which are insulated from each other and from the conductive outer shell, and each of which is integrally continuous with an inner conductor. Mounted within the envelope adjacent the three contact points is a mobile contact. The mobile contact is movable from outside the envelope to make or break a circuit between a selected transversely extending contact point and the common contact point. Actuator means pivotally mounted on the envelope and operatively connected to the mobile contact are provided to effect movement of the mobile

2

contact from outside the envelope to make or break a circuit through a selected pair of inner conductors.

In more specific detail, the miniature vacuum coaxial switch of my invention comprises a vacuumized envelope formed from an elongated hollow cylindrical metallic shell or tube 2 diametrically apertured intermediate its ends to accommodate axially aligned cylindrical conductive terminal sleeves 3. Each sleeve is formed with a reduced diameter portion 4 extending into the shell 2 through an aperture, and a relatively larger integral terminal portion 6 extending from the shell and provided with threads 7 adapted to receive a conventional coaxial connector (not shown), for connection of the switch in a coaxial transmission line. Each of the aligned terminal sleeves is hermetically brazed to the shell within the aperture so that a mechanically rigid and electrically continuous union is formed therebetween. The oppositely extending terminal sleeves 3 and shell 2 thus form an integral cruciform outer metallic conductor which completely shields the interior of the envelope from undesirable radiations.

Extending into one end of the cylindrical shell 2 and rigidly brazed thereto is a third terminal sleeve 8 having an inner end portion 9 of the same diameter as the portion 4 of each terminal sleeve 3. A reduced diameter cylindrical portion 12 integral with the inner end portion 9 and with the outer threaded terminal portion 13, fits snugly within the open end of the shell where it is rigidly and hermetically brazed.

Coaxially associated with and supported on each terminal sleeve 3 is an inner conductor 14 extending through the central aperture of an annular insulator 16 interposed transversely between the inner conductor and the conductive terminal sleeve 3. The insulator 16 is preferably a ceramic annulus having inner and outer peripheries 17 and 18 metallized and hermetically brazed to the inner conductor and terminal sleeve, respectively. Each inner conductor thus provides an inner end 19 constituting a fixed contact point within the envelope, and a portion 21 constituting a terminal lead extending out of the envelope. The inner conductor 14, like the sleeves 3 within which they are coaxially supported, are axially aligned and perpendicular to the longitudinal axis of the shell 2. Within the envelope, the inner ends 19 of the inner conductors are spaced apart, each terminating at a point radially spaced equally from the longitudinal axis of the shell.

A third inner conductor 22 is similarly coaxially associated with and supported on the third terminal sleeve 8, by an annular ceramic insulator 23 having an outer metallized periphery 24 hermetically brazed across the reduced diameter portion 12 of the sleeve, and an inner metallized periphery 26 hermetically brazed about the inner conductor 22. The outer end portion 27 of the conductor 22 constitutes a terminal lead extending out of the envelope, while the inner end 28 of the inner conductor extends into the envelope between the inner ends 19 of the conductors 14 to provide a fixed contact point common to both contact points 19. As shown in FIG. 1, the common contact point 28 is shaped to provide flat contacting surfaces 29 on opposite sides thereof, each parallel to the associated end of the contact point 19.

From the above it will be apparent that the sleeves 3 and 8, annular insulators 16 and 23, and inner conductors 14 and 22, cooperate one with the other and collectively with the shell 2, to hermetically close this end of the envelope. The cooperative combination of these elements also provides three separate switch terminals having inner and outer conductive elements coaxially arranged and integrally connected mechanically to give rigidity, while effectively electrically insulating the inner conductors one from the other and from the outer con-

ductor. The inner conductor 22 constitutes the common input terminal of the switch, and is related to surrounding structure in both proportion and position to maintain a uniformly low standing-wave-ratio through the switch.

Means are provided to hermetically seal the end of the shell 2 opposite the terminal sleeve 8, and to connect and disconnect the common contact point 28 with a selected adjacent contact point 19. Closing the lower end of the shell 2 is a flexible metallic bellows 31 extending into the shell 2 in a closed inner end 32, and at its outer open end 33 having a cylindrical flange 34 lying snugly within the shell adjacent the end thereof and hermetically brazed thereto.

Integrally united at its inner end 36 to the closed inner end 32 of the bellows and extending outwardly therefrom is a metallic stem 37. Adjacent its outer end portion 38, the stem is provided with an integral bearing 39 bored transversely of the stem to receive a pivot pin 41 having opposite end portions 42 journaled in the annular bearing mounting plate 43. Spaced lugs 44 on the bearing mounting plate abut opposite ends of and confine the stem bearing 39 to restrict movement thereof to pivotal movement in a single plane including the axes of the inner conductors 14 and 22. A cylindrical sleeve 46 brazed to the periphery of the bearing mounting plate serves to confine the pivot pin 41, and also extends beyond the mounting plate in a flange 47 snugly encircling and brazed about the lower end of the shell 2. Pivotal movement of the outer end 38 of the stem about the pivot pin 41 thus results in the inner end 36 of the stem, with bellows attached, being displaced from side to side within the envelope.

Movably mounted within the envelope on the inner closed end of the bellows is a U-shaped mobile contact having spaced resilient contact arms 48 integral with a base 49 which is in turn brazed to a metal cap 51 similarly brazed on the metallized upper end portion of a dielectric pillar or post 52. A metal cap 53 brazed to the metallized lower end of the post and to the closed inner end of the bellows insures a rigid and permanent mounting for the U-shaped mobile contact. The dielectric post is preferably high dielectric strength ceramic, and serves to effectively insulate the mobile contact from the operating mechanism.

In FIG. 1, the resilient arms 48 are shown to extend upwardly, one each extending between the common contact point 28 and the contact point 19 on each side thereof. The parts are proportioned so that when one of the arms 48 engages the contact point 19 with which it is associated, the other contact arm 48 engages the common contact point 28, thus completing a circuit therebetween. Movement of the mobile contact in the opposite direction results in the resilient arms being disengaged from the position shown and re-engaged between the common contact point 28 and the other contact point 19. In either position a portion of the mobile contact lies interposed between the engaged contact points and the disengaged contact point.

In the modified mobile contact structure illustrated in FIG. 4, each resilient arm 48 is provided on its upper end with an integral contact portion 54 adapted to engage and disengage the associated contact point 19. Integrally interposed between each contact portion 54 and the associated surface 29 of common contact 28, is a flexible and conductive metallic bellows 56. This integral interconnection results in the contact resistance being substantially halved, and the inductance being materially lessened. Additionally, interposition of the bellows makes it possible to reduce the spacing between each contact portion 54 and the associated fixed contact point, thus rendering the switch faster acting. Also favorably affected is the standing-wave-ratio through the switch.

Means are provided outside the envelope operatively connected with the stem 37 to selectively move the

mobile contact into and out of engagement with the fixed contact points. Schematically illustrated in FIG. 1 is a solenoid 57, having its armature 58 connected by links 59 to the outer end portion 38 of the stem. A recovery spring 61 connected with the armature and links, retains the mobile contact normally closed as shown. Energizing the solenoid causes the stem to be pivoted counterclockwise about the pin 41, thus tensioning the spring, which returns the mobile contact to its initial position when the solenoid is deenergized.

Evacuation of the rigid, hermetically sealed envelope is effected through tubulation 62 brazed over an aperture 63 in the shell 2. From the manner in which the stem 37 and bellows are cooperatively related it will be apparent that inward expansion of the bellows due to evacuation of the envelope is prevented by the stem, but due to its inherent flexibility, the inner end of the bellows is capable of being displaced from side to side. Because of its length in relation to the amount of lateral displacement, the stress and strain imposed on the bellows are negligible, thus contributing to a long bellows and switch life.

I claim:

1. A miniature vacuum coaxial switch comprising a vacuumized envelope including the outer metallic conductor of the switch, a plurality of inner conductors rigidly supported on the envelope and extending thereinto to constitute spaced contact points within the envelope and terminal leads outside the envelope, a mobile contact within the envelope movable from outside thereof to engage or disengage selected contact points, said mobile contact having portions thereof so positioned with respect to said contact points on the conductors that movement of the mobile contact to engage selected contact points shieldingly interposes one of said portions of the mobile contact between the engaged contact points and a disengaged contact point whereby power leakage to the disengaged contact point is prevented, and actuator means mounted on the envelope and operatively connected to the mobile contact to effect movement thereof to make or break a circuit through selected inner conductors.

2. The combination according to claim 1, in which said actuator means includes means insulating the mobile contact from the outer conductor.

3. The combination according to claim 1, in which said actuator means includes a stem pivotally mounted on the envelope, a flexible metallic bellows integrally interposed hermetically between the stem and the outer conductor, and means for insulating said movable contact from said stem and bellows.

4. A miniature vacuum coaxial switch comprising a vacuumized envelope including an outer metallic conductor constituting a hollow cruciform housing having at least three integral outer terminals, an inner conductor rigidly supported on the envelope and coaxially associated with each outer terminal and extending into the envelope to constitute spaced contact points within the envelope and terminal leads outside the envelope, a mobile contact within the envelope movable from outside thereof to engage or disengage selected contact points, said mobile contact having portions thereof so positioned with respect to said contact points on the conductors that movement of the mobile contact to engage selected contact points shieldingly interposes one of said portions of the mobile contact between the engaged contact points and a disengaged contact point whereby power leakage to the disengaged contact point is prevented, and actuator means pivotally mounted on the end of the housing remote from said outer terminals and operatively connected to the mobile contact to effect movement thereof to make or break a circuit through selected inner conductors.

5. The combination according to claim 4, in which an annular dielectric insulator is integrally and hermetically

interposed between each said inner conductor and the associated outer terminal.

6. A miniature vacuum coaxial switch comprising a vacuumized envelope including the outer metallic conductor of the switch, a plurality of inner conductors rigidly supported on the envelope and extending thereinto to constitute spaced contact points within the envelope and terminal leads outside the envelope, a mobile contact within the envelope having U-shaped spaced resilient arms movable from outside the envelope into and out of engagement with adjacent contact points, and actuator means mounted on the envelope and operatively connected to the mobile contact to effect movement thereof to make or break a circuit through selected inner conductors.

7. The combination according to claim 6, in which electrically conductive and flexible means are provided integrally connecting each said resilient contact arm with one of said contact points.

8. The combination according to claim 7, in which said means connecting each resilient contact arm with one of the contact points comprises a flexible metallic bellows.

9. The combination according to claim 6, in which said actuator means includes a stem pivotally mounted on the shell, a flexible metallic bellows hermetically interposed between the stem and the outer conductor, and means for insulating said mobile contact from said stem and bellows.

10. The combination according to claim 9, in which said means for insulating the mobile contact from the stem and bellows comprises a ceramic post interposed between the mobile contact and the bellows.

11. A miniature vacuum coaxial switch comprising an elongated metallic vacuumized shell having first and second integral transversely extending outer terminal sleeves

extending into the shell intermediate its ends, a third integral outer terminal sleeve extending into one end of the shell perpendicular to the first and second terminal sleeves, inner conductors coaxially arranged within the outer terminal sleeves and extending into the shell to provide spaced contact points within the shell and terminal leads outside the shell, an annular insulator integrally interposed hermetically between each inner conductor and the associated terminal sleeve, a mobile contact within the shell U-shaped to provide spaced resilient contact arms extending between adjacent contact points and movable to engage or disengage selected contact points to make or break a circuit therebetween, and actuator means movably mounted on the shell and operatively connected to the mobile contact to effect movement thereof to engage or disengage selected contact points.
